TEETHING RING

Morris Mann, Brooklyn, N. Y.

Application October 25, 1949, Serial No. 5,695

Term of patent 14 years

(Cl. D83—1)

To all whom it may concern:

Be it known that I, Morris Mann, a citizen of the United States, residing at Brooklyn, New York, in the county of Kings and State of New York, have invented a new, original, and ornamental Design for a Teething Ring, of which the following is a specification, reference being had to the accompanying drawing, forming part thereof.

In the drawing:

Fig. 1 is a front elevational view of a teething ring, showing my new design;

Fig. 2 is a side elevational view of the same; and

Fig. 3 is a top plan view of the same.

I claim:
The ornamental design for a teething ring, as shown.

MORRIS MANN.
